UNITED STATES PATENT OFFICE.

DANIEL J. O'ROURKE, OF CLAREMONT, NEW HAMPSHIRE, ASSIGNOR, BY MESNE ASSIGNMENTS, TO SULLIVAN MACHINERY COMPANY, OF BOSTON, MASSACHUSETTS, A CORPORATION OF MASSACHUSETTS.

PISTON-ROD PROTECTOR.

1,193,481.

Specification of Letters Patent. Patented Aug. 1, 1916.

Application filed September 27, 1911. Serial No. 651,520.

To all whom it may concern:

Be it known that I, DANIEL J. O'ROURKE, a citizen of the United States, and a resident of Claremont, county of Sullivan, and State 5 of New Hampshire, (whose post-office address is care of Sullivan Machinery Company, 50 Church street, New York, N. Y.,) have invented an Improvement in Piston-Rod Protectors, of which the following description, in connection with the accompanying drawings, is a specification, like characters on the drawings representing like parts.

This invention relates to rock drills and 15 particularly to means for removing the grit or dirt from the piston rod of such a drill and preventing it from entering the cylinder head and wearing the piston rod guides.

The invention will be best understood by 20 reference to the following description when taken in connection with the accompanying illustration of one specific embodiment thereof, while its scope will be more particularly pointed out in the appended claims.

25 In the drawings: Figure 1 shows a rock drill having applied thereto one embodiment of the invention; Fig. 2 is an end view on an enlarged scale of the holder for the wiping material; and Fig. 3 is a side elevation of the same.

Referring to the drawings and to the embodiment of my invention, I have therein shown for purposes of illustration a usual or conventional form of pressure fluid actuated rock drill having the cylinder 1, the piston 2, and piston rod 3. The end of the piston rod has secured thereto a tool holder chuck 4 to receive the drill steel not herein shown. The forward end of the cylinder 40 is provided with a piston rod guide which, as is usual in this class of devices comprises a split or other form of bushing 5 with which the piston rod has sliding engagement. The bushing provides a prolonged 45 guide for the piston rod and assists in maintaining it in the required alinement. The bushing is clamped to the cylinder by means of the head or shell 6 fitting the tapered exterior of the bushing and holding the same 50 in place by any suitable means such as the usual tie rods or bolts, not herein shown. A stuffing box is herein provided by means of the packing 7 located in a groove of the bushing and surrounding the piston rod.

In practice the bushing or other cylinder 55 head guide of the rock drill is apt soon to become worn through the dirt and grit in the form of pulverized rock dust which rises from the drilled hole and which is carried into the bearing on the surface of 60 the piston rod. This destroys the fit between the rod and its guide and materially decreases the efficiency and effectiveness of the drill.

To prevent the admission of grit to the 65 bushing and thereby to prolong its life and preserve the alinement of the reciprocating elements of the drill, I have herein provided means for removing the grit by automatically wiping the rod as the latter retracts or withdraws into the bushing. For this purpose the bushing 5 is prolonged so as to project below the retaining head or shell 6 and the projecting portion is provided with a groove in which is seated 70 the ring-like wall 8 of a cup or retainer adapted to hold wiping material 9 such as cotton waste or the like in a position to embrace the piston rod and cause the dirt and grit to be wiped therefrom. The wiping 75 material 9 is herein retained by means of bent fingers or prongs 10 which project from the ring-like wall 8 and are bent or curved to hold the wiping material in place. Obviously, however, any desired formation 80 may be employed. To apply the holder to the bushing the rim 8 is split so that it may be spread open and slipped over the chuck 4 and the end of the bushing and seated in the groove. When seated it is clamped into 85 position by means of the clamping bolt 11. If desired the holder may be stamped or otherwise formed out of relatively thin sheet metal and then rolled up into the shape shown or it may be cast or otherwise formed 90 of relatively heavier metal, and if the latter, may, if desired, be split into halves and clamped together by two diametrically opposite bolts.

A wiper holder constructed as described 100 is adapted to hold the waste or other wiping material at the end of the bushing and in the best position to protect the bushing from the action of the rock dust and grit.

While I have herein shown and described 105 for purposes of illustration one specific embodiment of the invention it is to be understood that the same may be varied within

wide limits without departing from the spirit thereof.

Claims:

1. In a piston rod swab, the combination with a cylinder of a piston, a piston rod, a guide bushing for the piston rod, the latter having a circumferential groove, a piston rod wiping device having a ring-like wall adapted to seat in the groove of the bushing, and means for clamping the wiping device about the bushing.
2. In a piston rod swab, the combination with a cylinder of a piston and piston rod, a guide bushing for the piston rod projecting from the end of the cylinder, a piston rod wiping device including a plurality of separated holding members for holding wiping material, and means for securing them to the end of the bushing to present

the wiping material to the piston prior to 20 its passage through the bushing.

3. In a piston rod swab, the combination with a piston and piston rod of a detachable wiper holder comprising a split ring member, means at one end of said ring member 25 for clamping the same to the engine to encircle the rod, and a plurality of holding fingers projecting from the opposite end of the ring member and adapted to hold the wiping material about the rod.

In testimony whereof, I have signed my name to this specification, in the presence of two subscribing witnesses.

DANIEL J. O'ROURKE.
